UNITED STATES PATENT OFFICE.

LOUIS ILLMER, JR., OF CINCINNATI, OHIO, ASSIGNOR TO ILLMER GAS ENGINE COMPANY, A CORPORATION OF DELAWARE.

GAS-ENGINE.

1,078,286.

Specification of Letters Patent. Patented Nov. 11, 1913.

Application filed April 4, 1907. Serial No. 366,289.

To all whom it may concern:

Be it known that I, LOUIS ILLMER, Jr., of the city of Cincinnati, county of Hamilton, and State of Ohio, have invented certain new and useful Improvements in Gas-Engines, of which the following is a full, clear, and exact specification, such as will enable others skilled in the art to which it appertains to make and use the same.

10 This invention relates particularly to certain improvements in a valve gear for a double acting two cycle gas engine, the construction and organization being such as will avoid the use of cams and admit of 15 positively operating or forcing the valve to move in both directions without the use of closing springs. To this end I employ a novel linkage, driven from an eccentric on the crank shaft or other moving parts 20 of the engine, by means of which the valves may be opened rapidly and their motion properly accelerated and retarded with respect to the inertia effects produced. In this manner I am enabled to produce a valve 25 motion exactly equivalent to that of a properly designed rotating cam drive but without the attendant disadvantages.

In the operation of valve gears for gas engines, particularly for engines of high 30 power, it is necessary to take due account of the inertia and momentum effects produced by the valve parts, as otherwise the mechanism will operate with violent knocks and prevent satisfactory operation. It is accordingly important to open the valve with 35 a gradually accelerated velocity, and, as the valve nears its open position to retard this velocity, thus starting the valve gradually from its seat until the highest velocity is 40 attained and then bringing the valve gradually to rest by the time it reaches its open position. The same principle applies upon closing the valve; that is, the valve should be allowed to start rapidly from its open 45 position but caused to seat gently by gradual retardation, in order to prevent the knock otherwise following the abrupt contact of the valve on its seat. My present invention is particularly effective in accomplishing 50 this result.

Besides dispensing with cams, the mechanism which I have devised, enables me to both positively open and close the inlet valve with ease and certainty of movement and 55 without opening the valve against the pres-

sure of powerful springs which are otherwise necessary to seat the type of valve to which this invention particularly relates. The inlet valves of large two cycle gas engines become quite massive and require very 60 rapid acceleration in order to open and close within the short time allowed for the charging operation of the power cylinder. Hence the positive or forced closing of the inlet valves forms an important feature of this 65 construction.

My invention involves various other features of more or less importance, all of which are fully set forth hereafter.

In the accompanying drawings, which 70 illustrate one manner in which my invention may be practically embodied: Figure 1 represents a vertical longitudinal section of the power cylinder of an engine, showing the location of the inlet valves. Fig. 2 is 75 a plan view of one longitudinal half of the engine, particularly illustrating the valve actuating mechanism. Fig. 3, is a side elevation with parts in section, on the line 3—3 of Fig. 2. Fig. 4 is an enlarged horizontal section of one of the power cylinders showing the parts adapted for positively actuating the inlet valve in both directions. Fig. 5 is a view of the linkage illustrating 80 its several critical positions by dotted radial 85 lines. Figs. 6, 7 and 8 are elevations of the locking device in its three critical positions.

Each end of the double acting power cylinder carries a puppet inlet valve 28, which valves are annular in form and encircle the 90 piston rod.

Referring particularly to Fig. 4 which shows the structure of the valve, it will be noted that the valve has a stem of tubular form, 29^a, formed integral therewith, and 95 which is adapted to slide in recessed parts of the housing 32. This housing is also provided with a seat bushing 31, tubular in form and inclosing the tubular valve stem. The bushing is spaced from the stem to form 100 a passage for the working charge into the power cylinder. For the purpose of communicating motion to the valve 28 the free end of the tubular stem 29^a is flanged and adapted to receive the two push rods 89. 105 These rods are of a length sufficient to extend outside of the valve housing parts and are joined by two sets of straps 92 in order to place the free end of the valve rocker 54 into operative connection with the 110

valve 28. The rocker 54 carries two arms, so as to straddle the piston rod and is centrally fastened to the rock shaft 55, through which shaft the motion for operating the 5 valve is transmitted.

In the preferred arrangement of the valve mechanism, the puppet valve is positively actuated both in opening and in closing. As shown in Fig. 1, the valves 28 may be closed 10 however, by means of the spring 50. In that case the valve rocker 54 may engage with the inlet flange parts by means of rollers 53 carried by the free ends of the rocker arms and thus operate the tappets 52 which 15 push open the valve and compress the spring 50.

The rock shaft 55 extends laterally across the axis of the power cylinder and is mounted in the frame parts of the engine. One of 20 the free ends of this shaft extends through its bearings and at its outer end carries a locking device, hereinafter described, which permits the eccentric and a portion of the valve gear mechanism to continue its motion while the puppet valve is permitted to 25 rest on its seat during the considerable portion of the engine cycle requiring the inlet port to remain closed.

The mechanism for imparting to the shaft 30 55 its characteristic motion will now be described.

Referring to Figs. 2, 3, 5, 6, 7, and 8 the element 56 designates a reach rod which is connected in any suitable manner with the 35 eccentric on the crank shaft or other moving parts of the engine, giving the reach rod a regular reciprocating motion in synchronism with the power piston movements. Such an eccentric is diagrammatically illustrated as 40 88 in Fig. 5. The reach rod 56 is articulated to the driving arm of the wrist plate 57 and said arm is also joined by a parallel rod 58 to the driving arm of a second wrist plate 57^a, identical in structure and function as 45 the first named plate. Each wrist plate oscillates about the wrist pin 59 and they are articulated respectively to the valve devices at the ends of the power cylinder. Each of the wrist plates is provided with a toggle 50 arm 57^b which is in turn articulated to the toggle link 60. In the construction shown, these links are shaped to clear the gas and air inlet ducts 33. The other ends of the toggle links 60 are respectively articulated 55 to the link arms 61, which are mounted loosely on the rock shafts 55. Said links carry pins 62 projecting laterally therefrom toward the engine cylinder for the purpose of coacting with the hooks 63. These hooks 60 are securely fastened to and adapted to move with the shaft arms 64 which arms are firmly secured respectively to the rock shafts 55, which shafts, as stated, are in operative connection with the valves 28. The hooks 65 63 curve upward into an overhanging position

with respect to the shaft arms 64. The arms 64 are also provided with locking toes 63^d which are firmly secured to these arms by bolts 63^b and adjustable toward and away from the same by the wedges 63^c. The toes 70 63^d are positioned opposite the engaging end or face of the hooks 63 so that the pins 62 may just enter between the hooks and the toes to impart motion from the toggle linkage to the puppet valve in either direction. 75 The hooks 63 and the toes 63^d, which transmit motion from the toggle linkage to the shaft arm 64 are so shaped as to yield slightly when the force is applied to these parts. The valves are furthermore operated through 80 rock-shafts 55 which also have a slight amount of torsional elasticity, thus the picking up of the valve parts is materially eased, especially when, on account of wear, the mechanism may not be in perfect adjustment. 85 The yielding character of these members is however, in no sense commensurate with the large amount of elasticity of the spring element required for spring closed valves and, in fact, performs entirely dissimilar functions. In order to counteract any whipping 90 action of the reciprocating valve parts that may be occasioned by the limited amount of elasticity in the rock shaft, the flanged end of the valve, 29^a, entering the annular recess 95 in the valve housing, may be made to serve as a dash pot to cushion the valve when seating.

The mode of action of the locking devices is shown in detail in Figs. 6, 7 and 8 which 100 represent successive critical positions of the head end parts of the gear. The link arm 61 rocks freely on the shaft 55 and causes the pin 62 to move in and out of engagement with the hook 63 and the toe 63^a, thus locking 105 the toggle link 60 with the shaft arm 64 and thus causing the toggled eccentric movements to be imparted to the puppet valves. It will be observed that the pin 62 does not actually engage with the hook 63 and the toe 63^a until the toggle link 60 is raised to its position of alignment with the toggle arm 57^b as indicated in Fig. 7. At all positions above that of alignment, the locking of the parts 62, 63 and 63^d is retained, and the shaft arm 64 is 110 operated by the pin 62. At all positions of the toggle link 60 below the position of alignment shown in Fig. 7, the pin 62 is disengaged from the hook 63 and the toe 63^a, and the link arm 61 moves freely on the rock 115 shaft 55 without imparting motion thereto.

The wrist plate 57^a under the action of the eccentric driven rods 56 and 58, operates with a rocking or oscillating motion. Through the medium of the toggle link 60, the wrist plate action imparts to the link arm 61, two oscillations or rocking movements for each complete oscillation or rocking motion of the wrist plate, resulting in the intermittent connection and disconnection of the pin 120 125 130

62 with the parts 63 and 63^a. For the purpose of a detailed explanation of this action, reference is now had to the diagram Fig. 5 and Figs. 6, 7 and 8.

Fig. 5 shows the linkage at the eccentric, outer dead center position, being one of the extreme positions of the toggle arm 57^b, to be known as position *a*. The Fig. 5 also indicates the two other characteristic positions of the gear by means of radial center lines, which positions will be known as *b* and *c*; the position *b* corresponding with the toggle alinement position while the position *c* corresponds with the eccentric, inner dead center, or other extreme position of the toggle arm 57^b. Figs. 6, 7 and 8, as noted thereon, correspond respectively with the positions *a*, *b* and *c* of Fig. 5.

Assuming the parts to be in position *c* (Figs. 5 and 8) the wrist plate 57^a is at the eccentric, inner dead center position, which is to say, the lowermost position of the toggle arm 57^b. The link arm 61 is now likewise moved down to its lowermost position, while the shaft arm 64 and the rocker 54 are in their extreme leftward positions, the corresponding puppet valve being closed and the pin 62 and the hook 63 and toe 63^a being disengaged. As the wrist plate 57^a reverses its movement the parts assume the toggle alinement position *b* (Figs. 5 and 7) which results in the upward movement of the link arm 61 and in the lifting of the toggle link 60 sufficiently to allow the pin 62 to engage with the toe 63^a and the hook 63. Further movement of the toggle causes the pin 62 to "pick up" or lock the shaft arm 64, which in turn causes the valve to open. The wrist plate 57^a then continues its movement until it reaches the eccentric outer dead center position *a* (Figs. 5 and 6). Here it will be seen that the shaft arm has been locked to the toggle link 60 and moved to a position to the right of the position *b* with the result that the shaft 55 has been correspondingly rocked, the valve rocker 54 moved toward the right and the inlet valve fully opened. The wrist plate then reverses its movement and returns the linkage to the toggle alinement position *b*, resulting in the return of the parts 60, 61, 62, 64 and 54 to the position shown in Fig. 7 and thus causing the puppet valve to follow and seat itself by reason of the pin 62 acting against the toe 63^a. The valve is therefore positively operated in both the opening and closing movements. The link mechanism continuing its movements under the reverse motion of the wrist plate, causes the toggle link 60 to drop from the position *b* with the result that the pin 62 is disengaged from its locking devices 63 and 63^a but the shaft arm 64 and the valve rocker 54 remain in the position *b* which is the position of valve closure. The

wrist plate then continues its movement until the linkage parts return to the position *c*, the eccentric inner dead center position, and thus completing the cycle of operations of the valve gear. During such cycle the 70 wrist plate has made two movements, or one complete oscillation while the guide arm has made four movements or two complete oscillations, these four movements of the link arm 61 resulting first, in a movement 75 alongside the shaft arm 64 so that the locking device may pick up the shaft arm; second, in a movement to the right carrying the arm 64 along and opening the valve; third, in a movement to the left carrying the arm 64 back and allowing the valve to seat; and fourth, in a movement downward and to the right, disconnecting the locking device to allow a time interval before the return of the arm 61 at the beginning of the next 80 cycle of operations. By this means the eccentric may be kept in motion continuously while the puppet valve receives intermittent motion so as to allow the valve to remain on its seat during approximately three- 85 fourths of a revolution of the engine. As the eccentric reaches the position corresponding to *b* the toggle link 60 will be moving rapidly in a direction normal to the center line of the alined toggle pins, thus throwing the locking elements 62, 63 and 63^a into 90 rapid engagement. At the same time the toggle arm 57^b and the toggle link 60, being in alinement, the pin 62 will have practically no velocity component in the direction of 95 the center line of the alined toggle pins, consequently the motion imparted to the inlet valve at this instant causes the valve to open with the desired gradually accelerated motion. When the wrist 100 plate is moving approximately midway between the positions *a* and *b*, the valve will be traveling with its maximum velocity. Thereafter the valve velocity is gradually retarded, due to the fact that the eccentric approaches its outer dead center position, which brings the valve gradually to rest as it reaches its open position. Upon the return of the wrist plate and the other 105 before described operations incident thereto, 110 the same effects are produced in the reverse direction and as the toggle joint again approaches its alinement position, the valve 115 is gradually brought to rest and properly seated.

It will be observed that while the linkage moves from position *a* to position *b*, the shaft arm 64 is positively actuated through the medium of the toe 63^a and by the arrangement which I have before described, 125 the positive movement of the arm 64 is then transmitted directly to the valve. The inlet is therefore forced shut by the positive action of the toe 63^a coacting with the pin 62 which moves with the valve gear linkage. 130

In order to exert an initial pressure on the valve seat after the valve has been brought to rest, I provide an expansive spring 93 (Fig. 4). This spring acts between two relatively slidable members 94 and 95, one of which is pivoted to a stud 96 projecting from one arm 54 while the other is pivoted to a stud 97 projecting from the valve housing. In view however, of the positive nature of the valve driving mechanism, this spring performs no necessary function in closing the valve. The spring 93 may, in fact be dispensed with since the piston compression created in the power cylinder of a two cycle engine immediately upon the inlet valve closure is sufficient to hold the valve on its seat until it is again reopened by the gear.

The engine shown is intended to operate according to the two stroke cycle and the inlet valves are opened each time that the exhaust ports are overrun by the piston; the inlet valves may be actuated and so timed by the valve gear. It is clear however that this gear may be used for other purposes than that shown in the drawings and also that the elements 57, 60, 61 and 64 may be reversed or modified without departing from the spirit of the invention.

What I claim is:—

1. In an engine valve gear the combination of a puppet valve, a toggle linkage for actuating the valve comprising a pivoted toggle arm and a link, means for oscillating the toggle linkage, the alined position of the toggle arm and the link being intermediate the two dead center positions of the toggle arm, and means for forcing the valve shut by the movement of the toggle from one of its dead center positions to its alined position.

2. In an engine valve gear the combination of a puppet valve, a toggle linkage for actuating the valve comprising a pivoted-toggle arm and a link, means for oscillating the toggle linkage, the alined position of the toggle arm and the link being intermediate the two dead center positions of the toggle arm, means for forcing the valve open by the movement of the toggle arm from its alined position to one of its dead center positions and for forcing the valve shut by the return movement to its alined position.

3. In an engine valve gear the combination of a puppet valve, a toggle linkage for actuating the valve comprising a pivoted toggle arm and a link, means for oscillating the toggle linkage, the alined position of the toggle arm with the toggle link being intermediate the two dead center positions of the toggle arm, means for forcing the valve open by the movement of the toggle arm from its alined position to one of its dead center positions and for forcing the valve shut by the return movement to its alined position, and means maintaining the valve on its seat dur-

ing the movement of the toggle arm to and from its opposite dead center position.

4. In an engine valve gear the combination of a puppet valve surrounding the piston rod, a rock shaft in operative connection with the valve, a toggle linkage for actuating the rock shaft comprising a pivoted toggle arm and a link, means for oscillating the toggle linkage, the alined position of the toggle arm and the link being intermediate the two dead center positions of the toggle arm, means for forcing the valve open by the movement of the toggle arm from its alined position to one of its dead center positions and for forcing the valve shut by the return movement to its alined position and means maintaining the valve on its seat during the movement of the toggle arm to and from its opposite dead center position.

5. In an engine valve gear the combination of a puppet valve, a rock shaft, a valve rocker fixed to the rock shaft and in operative connection with the valve, a shaft arm fixed to the rock shaft, a toggle linkage comprising a pivoted toggle arm and a link, a link arm loosely mounted on the rock shaft and articulated to the free end of the toggle link, means for oscillating the toggle arm, the alined position of the arm and link being intermediate the two dead center positions of the toggle arm, means locking the shaft arm to the link arm whereby to force open the valve by the movement of the toggle arm from its alined position to one of its dead center positions and to force the valve shut by the return to its alined position, and means for disengaging the locking device during the movement of the toggle arm to and from its opposite dead center positions.

6. In an engine valve gear the combination of a puppet valve, a rock shaft in operative connection with said valve, a toggle means actuating the rock shaft to force the action of the valve in both directions and means for automatically locking the toggle means when it assumes its alined position and maintaining said locked position during the travel of the toggle from the alined position to and from one of its dead center positions and breaking said locked position during the travel of the toggle from alined position to and from the opposite dead center position.

7. In an engine valve gear the combination of a puppet valve, a rock shaft in operative connection with the valve, a shaft arm fixed to the rock shaft, a toggle linkage for actuating the shaft arm, comprising a pivoted toggle arm and a link, a link arm loose on the rock shaft and articulated to the free end of the link, and means locking the free end of the toggle link directly to the shaft arm at predetermined periods of the gear cycle.

8. In an engine valve gear the combina-

tion of a puppet valve having a tubular stem surrounding the piston rod, a flange formed integral with the stem, a set of push rods engaging with the flange, a rock shaft, a 5 valve rocker fixed to the rock shaft, a set of straps connecting the push rods to the valve rocker, a toggle linkage means for oscillating the rock shaft whereby the valve is intermittently forced in both its opening 10 and closing movements.

9. In an engine valve gear the combination of a puppet valve, a toggle linkage for actuating the valve comprising a pivoted toggle arm and a link, a link arm articulated to the free end of the link, means for oscillating the toggle link arm whereby the link arm is made to assume its extreme position in one direction upon alinement of the 15 toggle arm and the link, said toggle arm being movable to each side of the alined position whereby one complete oscillation of the toggle arm imparts two such oscillations to the link arm, means for forcing the valve open and shut during the first oscillation of the link arm and means maintaining the valve on its seat during the second oscillation of the link arm.

10. In an engine valve gear, the combina-

tion of a puppet valve, a rock shaft, a valve rocker fixed to the rock shaft and in operative connection with the valve, a shaft arm also fastened to the rock shaft but spaced from the valve rocker, a toggle linkage for actuating the shaft arm comprising a pivoted toggle arm and a link, means for oscillating the toggle arm, the shaft arm being made to assume its extreme position in one direction upon alinement or dead center position of the toggle and the link, and said link being movable to each side of said 30 alined position, whereby one complete oscillation of the toggle arm imparts two such oscillations to the shaft arm, means forcing the valve open during the first half of the oscillation of the shaft arm and forcing the 35 valve shut during the second half of said oscillation, and means maintaining the valve on its seat during the remaining period of the gear cycle.

In testimony whereof I have signed my 40 name to this specification in the presence of two subscribing witnesses.
